UNITED STATES PATENT OFFICE.

JOHN D. LUTTRELL, OF BENTON HARBOR, MICHIGAN, ASSIGNEE TO SERVICE CARBIDE
LAMP COMPANY, OF TERRE HAUTE, INDIANA, A COPARTNERSHIP.

ACETYLENE-GAS GENERATOR.

1,336,573.

Specification of Letters Patent. Patented Apr. 13, 1920.

Application filed February 19, 1919. Serial No. 277,991.

To all whom it may concern:

Be it known that I, JOHN D. LUTTRELL, citizen of the United States, residing at Benton Harbor, in the county of Berrien and 5 State of Michigan, have invented certain new and useful improvements in Acetylene-Gas Generators; and I do hereby declare the following to be a full, clear, and exact 10 description of the invention, such as will enable others skilled in the art to which it app- pertains to make and use the same.

This invention relates to improvements in acetylene gas generators and more particu- 15 larly to that type of acetylene gas generators which are embodied in portable lamps for the use of miners and elsewhere where de- 20 vices of this character are usually employed.

The invention has for its particular object to provide a generator of this character 25 which will generate gas at a uniform rate sufficient to supply a burner of predeter- 30 mined consumption with a uniform quantity and pressure of gas and which will not waste such gas.

A further object of the invention is to 35 provide a gas generator of the character aforesaid which is very simple and cheap in construction, easily controllable and which may be discontinued from operation at will 40 in a very simple manner.

The invention consists in the features of 45 construction and combinations of parts hereinafter fully described and particularly claimed.

In the accompanying drawings illustrating 50 a suitable embodiment of the invention:

Figure 1 is a view in side elevation of a 55 portable gas generator or lamp constructed in accordance with the invention.

Fig. 2 is a vertical longitudinal section of 60 the same on the line 2—2 of Fig. 1.

Fig. 3 is a plan section of the same on the 65 line 3—3 of Fig. 2.

Fig. 4 is a fragmentary detail perspective 70 view partly in section showing the plunger carrying the lamp wick or moisture feeding device.

Referring now to said drawings, 1 indicates 75 the cylindrical housing or casing of the lamp. This may be made of any ordinary tubular element which is provided at one end with an integral head 2 provided with a boss 3 adapted to contain burner tip 4. Said casing is open at its other end and may 80 be suitably sealed, as for example by means

of the plug 5. Within the housing there is contained a removable receptacle 6 for water which is preferably equipped with a screw cap 7 having an aperture therein eccentric thereof and into which a tubular ele- 60 ment 8 is fitted and suitably secured by soldering or the like. Mounted to slide or reciprocate within said tubular element 8 is a rod 9 terminating at its upper end in a plug 10 of a yielding material, preferably cork. 65 About the rod 9 there is wound and suitably secured a wick 11 preferably of the ordinary type used in lamps, said wick being adapted to be withdrawn from and inserted into the bottom of the receptacle 6 by means of the 70 rod 9 and the extent of its projection from the receptacle 6 being determined by the position of the rod 9 with reference to the tubular element 8. Said wick snugly fits the tube 8 so as to prevent free flow of water 75 therefrom when the receptacle 6 is inverted.

The receptacle 6 is adapted to contain 80 water which is fed by capillary attraction to maintain the exposed portion of the wick 11 projecting from or above the tubular ele- 85 ment 8 continuously moist.

The receptacle 6 is preferably substan- 90 tially one-third the length of the casing 1. The latter is adapted to be inverted after the plug 5 and receptacle 6 have been re- 95 moved therefrom and a quantity of calcium carbid introduced into the same to fill it about one-third of its total capacity. There- 100 upon, the receptacle 6 with the wick 11 and the rod 9 projecting therefrom a prede- 105 termined distance, is inserted into the re- 110 ceptacle and the plug 5 thereafter inserted. The casing 1 is then turned to its normal position whereupon the lumps of carbid contained in the casing 1 will be brought

more or less in contact with the moist wick 11 thus generating gas which will speedily create a pressure within said casing 1 and be discharged from the orifice of the burner 4. As the carbid is decomposed the calcic 100 residue will drop down upon the top of the receptacle 6 and fresh carbid will be auto- 105 matically brought into contact with the wick 11 thereby continuing the generation of gas.

In practice it has been found that such gen- 110 eration will proceed at a very uniform rate and will be governed as to volume by the length of area of the wick 11 protruding from the mouth of the tubular element 8. Such generation will continue practically

- uniformly so long as any undecomposed carbid remains in the casing 1. The rate of gas generation can be readily regulated by increasing or decreasing the extent of 5 projection of the wick 11 from the tubular element 8 and such generation may be caused to entirely discontinue by removing the receptacle 6 from the casing and inserting the rod 9 and wick 11 into the same until the 10 plug 10 seals the mouth of the tube 8. The receptacle and plug may then be reinserted into the casing 1 whereupon no further gas generation due to feeding of moisture from the receptacle 6 will occur. Some further 15 generation may result from moisture which has been absorbed by the calcic residue of the decomposed carbid, but as soon as such moisture has been substantially exhausted all generation of gas will cease.
- 20 In practice it is found that by means of this apparatus all of the carbid is decomposed at a uniform rate and that the calcic residue is reduced to substantially a relatively dry powder in place of a wet mass 25 which is difficult of removal. The calcic residue is readily removed by means of any ordinary instrument such as a stick serving to loosen it from adhesion with the walls of the casing 1.
- 30 While I have shown the preferred embodiment of the invention in the accompanying drawings, it will be obvious, of course, that changes in details of construction may be effected without disturbing the 35 relative arrangement of the parts or in any way affecting the mode of operation above set forth and without departing from the invention as defined in the appended claims.
- The casing 1 may be equipped with a hook 40 12 as shown in Fig. 1 or with any other suitable means for suspending the same from a support for rendering it convenient to handle.

I claim as my invention:

1. An acetylene generator comprising a 45 housing adapted to contain carbid and having a gas discharge orifice, a container for water in the bottom of said receptacle, a reciprocable element mounted in the top of said water receptacle and adapted to be projected therefrom, a lamp wick or the like mounted on said reciprocable member and adapted to be kept moist by capillary attraction, the carbid adapted to contact with the projecting portion of said wick for generating 50 gas and means on said reciprocable element for sealing the water-chamber to prevent feed of water to the carbid chamber.

2. An acetylene generator comprising a 55 housing adapted to contain carbid and having a gas discharge orifice, a container for water in the bottom of said receptacle, a tube mounted in the top of the water chamber adjacent to its peripheral edge, a rod covered with an absorbent fabric reciprocably mounted in said tube and adapted to be projected therefrom varying distances 60 into the mass of carbid contained in said casing for feeding water to the carbid in contact with the absorbent fabric to generate 65 gas.

3. An acetylene generator comprising a 70 housing adapted to contain carbid and having a gas discharge orifice, a container for water in the bottom of said receptacle, a 75 tube mounted in the top of the water chamber adjacent to its peripheral edge, a rod covered with an absorbent fabric reciprocably mounted in said tube and adapted to be projected therefrom varying distances 80 into the mass of carbid contained in said casing for feeding water to the carbid in contact with the absorbent fabric to generate gas and a plug for sealing the tube mounted on the outer end of said rod.

JOHN D. LUTTRELL.
